UNITED STATES PATENT OFFICE.

FREDERICK S. PINKUS, OF NEW YORK, N. Y.

DESIGN FOR A NAPKIN OR TABLE-CLOTH.

SPECIFICATION forming part of Design No. 21,080, dated September 29, 1891.

Application filed September 1, 1891. Serial No. 404,465. Term of patent 3½ years.

To all whom it may concern:

Be it known that I, FREDERICK S. PINKUS, a citizen of the United States, and a resident of New York, in the county and State of New York, have invented and produced a new and original Design for Napkins and Table-Cloths, of which the following is a full, clear, and exact description.

In the accompanying drawing the figure 10 shows in plan a portion of a napkin containing the design.

The leading feature of my design is a group of rings or circles interlaced. The groups may be of two sizes, the smaller groups appearing at intervals within a border, while at greater intervals the larger groups appear, one at the center, one at each corner, and one

on the line of the border centrally between these at the corners. One or more of the rings may contain the word "Pullman" or 20 any other word, according to the use of the article; but of course this forms no part of the invention, being varied as desired or omitted altogether.

I claim—

The design for a napkin or table-cloth herein shown and described.

In testimony whereof I affix my signature in presence of two witnesses.

FREDERICK S. PINKUS.

Witnesses:

W.M. C. PHILLIPS,
W.M. LOW.
